UNITED STATES PATENT OFFICE.

FRANK HARVEY MILLER, OF MONTGOMERY, ALABAMA.

UNION SUIT.

1,404,629.

Specification of Letters Patent. Patented Jan. 24, 1922.

Application filed October 16, 1920. Serial No. 417,315.

To all whom it may concern:

Be it known that I, FRANK H. MILLER, a citizen of the United States, residing at Montgomery, in the county of Montgomery and State of Alabama, have invented certain new and useful Improvements in Union Suits, of which the following is a specification.

This invention relates to improvements in apparel and while it was particularly devised to furnish an improved garment for children, nevertheless a garment constructed according to my invention, may be used for various purposes.

15 The principal object of the invention is to provide a garment of simple and inexpensive construction, which may be easily and speedily placed on or removed from the wearer.

20 A further object of the invention is to provide a bifurcated garment in which two buttons only are employed for the purpose of securing the waist and the rear panel of the trouser portion in place.

25 With the foregoing objects outlined and with other objects in view, which will appear as the description proceeds, the invention consists in the novel features hereinafter described in detail, illustrated in the 30 accompanying drawing and more particularly pointed out in the appended claims.

Referring to the drawings:

Fig. 1 is a perspective view of one form of the garment as worn upon the person.

35 Fig. 2 is a front view of the improved garment.

Fig. 3 is a rear view of the same, with the rear flaps and panel closed.

Fig. 4 is a rear view of the garment with 40 the flaps opened and the panel lowered.

Fig. 5 is a detail view of a slight modification.

Fig. 6 is a detail sectional view of the modification.

45 In the drawing, 1 represents a bifurcated union garment which, in the present instance, comprises a shirt or waist portion 2, having a solid or unbroken front and a back formed of a plurality of overlapping flaps

50 3. Each of the flaps 3 has an outwardly inclined side edge 4 and an arc shaped lower edge 5, the length of the latter being substantially the same as the distance between the opposite sides of the garment.

55 The garment also includes a trouser por-

tion 6, the upper edge of the front of which is connected to the lower edge of the front of the shirt portion and a waist band 7 is provided between these edges. This waist band is provided in the preferred embodiment of my invention as shown in Figs. 1 to 4, inclusive, with two buttons 8 which are arranged at the opposite sides of the trouser portion. The flaps 3 of the shirt portion of the garment, are provided at their corners with button holes 9 which, when the flaps are overlapped, are designed to engage with the buttons 8 for the purpose of holding the flaps in overlapped position to form the rear of the shirt portion.

60 The trouser portion 6 is provided with a drop flap or panel 10 provided at its corners with button holes 11 designed to receive the buttons 8 after the flaps 3 have been secured to the same.

65 From the foregoing I believe the basic idea of my invention will be readily understood, but to render the same absolutely clear, I may state that in placing the garment on the wearer, the legs are first placed 70 through the bifurcated portion of the trousers 6, the arms are then inserted in the sleeves 12, and then the flaps 3 are folded and overlapped across the back and secured to the buttons 8. Finally the rear flap or 75 panel 10 is moved upwardly and secured to the buttons 8. It will be noted that the arc shaped edges project below the waist line, when the flaps are overlapped, and this downwardly extending part prevents 80 exposure to the person should the panel 10 sag.

85 In the modification of the invention shown in Figs. 5 and 6, the buttons 8^a instead of being secured to the waist band, are 90 provided at the corners of the flaps 3^a and the waist band and panel are provided with button holes 9^a and 11^a through which these buttons are inserted. With this construction, the flaps 3^a are overlapped across the 95 back and the buttons at their ends are inserted through the button holes 9^a, and finally the buttons are placed through the button holes 11^a to hold the rear panel in place, or one end of flap 3^a can be thus arranged with button and end of other flap with button hole as first described.

100 105 110 While I have described and illustrated the preferred embodiment of my invention, I am aware that various changes and modifica-

tions may be made in the embodiment shown without departing from the spirit of the invention as set forth in the claims.

The invention possesses the following advantages over garments now in general use. First, it is of simple design and easily donned or removed. Second, the construction is suitable for union underwear for adults and children and it may be used in making outer garments for children as well as working suits and overalls for adults. Third, it can be placed on the wearer without putting the garment over the head. Fourth, the overlapping flaps at the rear provide extra warmth for the kidneys and vital organs in cold climates, while affording additional protection to the spine in hot climates. Fifth, the entire suit can be fastened on with a minimum of two buttons, easily accessible. Sixth, the lower edges of the two overlapping flaps, preferably extend below the waist line, so as to keep the body protected in case the top of the drop flap when buttoned, should sag across the back. Seventh, the back flap or drop panel may be provided with additional button holes, so that the waist may be readily adjusted to accommodate persons of different sizes.

30 What I claim and desire to secure by Letters Patent is:—

1. A bifurcated garment including a shirt portion and a trouser portion, the shirt portion being provided with overlapping flaps, each flap extending from the top of the garment to the waist line and having a lower edge which extends from one side of the garment to the opposite side, a drop rear panel provided at the rear of the trouser portion, and a single fastening means connecting a corner of the panel and a corner of one of said flaps to the waist line portion of the garment at one side of the garment.

2. A union garment including an upper shirt portion and a lower portion connected thereto by a waist band, the shirt portion being provided with overlapping flaps, each flap extending from the top of the garment to the waist line and having a lower edge which extends from one side of the garment to the opposite side, the lower portion being provided with a drop panel, and fastening means securing the corners of the flaps and

the corners of said panel to the waist band portion of the garment at the sides of the 55 garment.

3. A bifurcated union garment including a shirt portion and a trouser portion, the shirt portion being provided at its rear with overlapping flaps, each of which is provided 60 with a downwardly and outwardly inclined side edge and a substantially horizontal lower edge, the lower edge extending from one side of the garment to the opposite side, the rear of said trouser portion being provided with a drop flap, and fastening means 65 securing the corners of the flaps and the corners of said panel to the waist band of the garment at the sides of the garment.

4. A bifurcated union garment including 70 a waist portion having a waist band, overlapping flaps forming part of the waist portion and provided at the rear of the garment, each flap extending from the top of the garment to the waist line and having a 75 lower edge which extends from one side of the garment to the opposite side, a trouser portion, a drop panel for the trouser portion, and a single button for securing one 80 of the corners of one of said flaps and one of the corners of the panel to the waist band of the garment at one side of the garment.

5. A bifurcated garment including a waist portion having a waist band, overlapping flaps forming part of the waist portion and 85 provided at the rear of the garment, each of said flaps having a side edge which is inclined downwardly and outwardly from one side of the neck portion to the opposite side of the waist band, and each flap having 90 a lower edge which extends from one side of the garment to the opposite side, a trouser portion having its front secured to the waist band and its rear provided with a drop seat panel having an upper edge which extends 95 from one side of the garment to the other side, a single fastening means connecting the corner of one flap to one of the corners of the drop seat panel, and a single fastening means connecting the corner of the other flap to the other corner of the panel, said fastening means constituting the only fastening for securing the garment on the wearer's body.

In testimony whereof I affix my signature.
FRANK HARVEY MILLER.
